LID VISE

Seth H. Hofheins, Box 116, Jemez Springs,
N. Mex. 87025
Filed Apr. 9, 1965, Ser. No. 446,903
2 Claims. (Cl. 81—3.3)

The invention relates generally to a lid vise and particularly to a novel device for loosening and tightening jar lids of any size, which is simple in design while offering maximum capabilities in performing its intended function.

Prior known lid vises have inherent in their structure many disadvantages which are overcome by the structure and advantages of the present invention. The common lid vise well known on the commercial market includes a pair of arms pivotably secured to one another and disposed for receiving a lid therebetween. Such devices do not provide adequate holding power to the lid and consequently are incapable of performing their task properly. This is due primarily to the small amount of area which is grasped by the arms, since they contact the lid at only two points on its periphery. Therefore, a considerable amount of force is required to produce adequate leverage between the arms to perform the more difficult tasks. The housewife, however, cannot always provide a great amount of force and, as a result, the device does not attain its intended function. Furthermore, since such devices contact the periphery of the lid at only two points, damage may result to both the lid and the jar by the excessive pressures which must often be applied. It can also be realized that the lid will bend at these two points of contact with the arms, thus providing more friction between the lid and the jar and consequently more resistance to the removal of the lid. Those devices which include structure for holding a larger portion of the periphery of a lid, however, overcome the above-mentioned disadvantages but are inadequate in several other aspects.

For instance, such devices cannot perform their function on a large variation of lid sizes without some adjustment being made to their structure for each size to be accommodated. Furthermore, those devices which have a small degree of variance for adapting to some different sizes of lids, require additional structure for providing leverage to the lid holding means before the device can perform its intended function. That is, structure is provided in devices of this character which will allow loosening of the lid holding means to allow its receiving a lid and then tightening it again to hold the lid properly. Such leverage structures are to the disadvantage of the user or operator, since both hands must be employed in effecting its operation and additional steps must be performed in manipulating the lid holding means.

In addition, the prior known devices of this character have not been adapted for installation on a cabinet or similar kitchen structure. The lack of this feature further prohibits the effective and efficient use of the device by the housewife. It can be realized, therefore, that the prior known articles for loosening and tightening lids either require the use of both hands of the operator to perform the intended function or require some form of adjustment in the structure to adapt to various sizes of the lids. It is, of course, a primary consideration to the housewife to have a device of this character including a self-sizing, endless chain on a heart-shaped means that can be operated with one hand and that does not require any adjustment with different sized lids.

It is therefore a primary object of this invention to provide a device for loosening and tightening jar lids that does not require any adjustment for various sizes of the lids.

2

It is another object of this invention to provide a device for loosening and tightening jar lids that can be operated effectively with the use of only one hand of the operator.

5 Another object of the present invention is to provide a device for loosening and tightening jar lids which can be easily installed under a cabinet or similar kitchen structure while providing effective operation in its function.

Still another object of the present invention is to provide a device for loosening and tightening jar lids which will grasp a large area of the periphery of the lid.

Another object of the invention is to provide a device for loosening and tightening jar lids which will not squeeze the jar lid at any particular point thus eliminating any increased resistance between the lid and the jar.

A still further object of the present invention is to provide a device for loosening and tightening jar lids which will increase the friction on the lid with increased turning force on the jar and without respect to the size of the jar lid.

These and other objects of the present invention will be more fully realized from the novel structure thereof which includes a base member adapted to be connected to a cabinet or similar kitchen structure. One side of the base member has the same shape as the top of a heart or a pair of adjoining epicycloids; that is, the ends are arcuately shaped and one side between the ends is V-shaped. A slot is provided in the one side and extends through the base to both ends thereof. A bearing is secured to the base member adjacent the apex of the V-shaped portion and intersects the slot and an endless chain or an endless friction belt which is pivotably mounted thereon. The chain is mounted at an intermediate point to provide a loop for receiving a jar lid. The V-shaped portion and the arcuate ends include means for providing frictional engagement with the lid preferably in the form of a roughened edge.

The invention will be more fully realized and understood from the following detailed description when taken in conjunction with the accompanying drawings wherein like reference numerals designate the same element, and wherein:

FIGURE 1 is a top view of the invention showing two positions of the endless chain or endless friction belt for respective different sizes of jar lids, as applied to a paired epicycloid contour with friction gripping means;

FIGURE 2 is a sectional view taken along lines 2—2 of FIG. 1 without the jar lids and endless chain, and illustrates the mode of attaching the device to a cabinet or similar structure; and

FIGURE 3 is a sectional view taken along lines 3—3 of FIG. 1, further illustrating the attachment of the device to a cabinet and showing some details of a preferred embodiment of the present invention.

55 With reference to the figures, there is shown a base member 10 adapted for attachment to the underside of a cabinet 11 or similar structure by screws 12, 12. An end 14 and the other end 16 of the base member are essentially arcuately shaped or heart-shaped or epicycloid-shaped and the edges contain a plurality of protruding portions 18 which constitute a friction engaging surface thereon. On one side of the base member 10 is a V-shaped portion 20 having slightly concavely arcuate sides which contain also a plurality of protruding edges 18 for providing a friction engaging surface thereon. A longitudinal slot 22 defined by side walls 24, 24 and a rear wall 26 extend between ends 14, 16.

70 A bearing or pivot member 28 is secured at a mid-point of the base member between the ends and provides a mounting means for a friction belt or endless chain 30. Chain 30 is mounted on the pivot member to pro-

vide a loop for receiving a jar lid 32. The longitudinal slot 22 is better illustrated in FIG. 2 as being defined by side walls 24, 24, and rear wall 26. The bearing member 28 extends through slot 22 and provides a mounting for chain 30 whereby the chain will be free to travel within the slot. The relationship between chain 30, bearing member 28, and slot 22 is also illustrated in FIG. 3, as well as the engagement between chain 30 and lid 32 and the attachment of the device to a cabinet 11. Endless chain 30 also includes a plurality of protrusions or gripping aid means 36 which constitute a friction means thereon for providing frictional engagement with lid 32 of a jar 38.

The operation of the device is simple and unique. The jar 38 having lid 32 thereon is inserted into the loop formed by the endless chain 30. This insertion is unobstructed and easily accomplished when the chain extends directly forward of the V-shaped portion 20. If the lid is to be removed from the jar 38, the chain is pulled to the left side of the device. For tightening the lid, jar 38 and the endless chain 30 are pulled to the right side of the device, as shown in FIG. 1, where it is assumed that the device is viewed from the bottom. Protrusions or gripping aid means 36 and edges 18 cooperatively grasp lid 32, and as a firm turning force is applied to the jar, the amount of grasping force increases uniformly around the lid. This action results from the jar tending to move along the surface of the V-shaped portion or the end as it is rotated. The lid moves a small distance along this surface and increases the tension on the endless chain 30, thereby increasing the grasping force of protrusions 36 and edges 18. The larger lids are accommodated on the surface of the V-shaped portion, and the smaller lids on the arcuate ends. Screws 12, 12 separately provide a fulcrum for the endless chain 30 when a very small lid is to be loosened or tightened. As the endless chain 30 is bent around screw 12, it pulls lid 32 into closer relationship to the end for frictional engagement with edges 18. Since the endless chain will remain substantially in a horizontal plane at all times, it can be realized that a jar lid can be inserted into the loop with only one hand. The jar is then moved to the proper side and turned until the desired result is accomplished.

As shown in FIG. 2 and particularly in FIG. 3, the device is ideally adapted for being secured to a cabinet structure 11. The device may extend from the edge of

the cabinet, as shown in FIG. 3, or it may be secured entirely under the cabinet out of sight, since no structure of the device nor the lid will extend beyond the side of the base member adjacent the cabinet to interfere with its operation.

5 The principles of the invention explained in connection with the specific exemplification thereon will suggest many other applications and modifications of the same. It is accordingly desired that in construing the breadth of the appended claims, they shall not be limited to the specific details shown and described in connection with the exemplification thereof.

10 What is claimed is:

15 1. A device for loosening and tightening lids comprising an epicycloid-shaped base member having a pair of arcuate ends and a longitudinal slot therein, a bearing member secured to said base at a mid-point between the ends and intersecting said slot, an endless chain mounted at one portion thereof on said bearing member to form 20 a loop disposed for receiving a lid, securing means for said base member extending through said slot in the arcuate ends and engageable with said endless chain the outer edges of epicycloid portions of said base and the endless chain including means for providing cooperative 25 frictional engagement with a lid.

2. A device for loosening and tightening lids comprising an epicycloid-shaped base having a pair of arcuate ends and a longitudinal slot therein, a bearing member secured to said base at a mid-point between the ends and 30 intersecting said slot, an endless chain mounted at one portion thereof on said bearing member to form a loop disposed for receiving a lid, said base member having securing means engaging the chain to reduce the loop area thereof, the outer edges of the epicycloid portions 35 of said base and the endless chain including means for providing cooperative frictional engagement with a lid.
